HOLDING MEANS FOR PROJECTILE FINS

Evelyn Cecil Muschamp d'Assis Fonseca, Bristol, England, assignor to The Bristol Aeroplane Company Limited, Bristol, England, a British company

Application February 16, 1949, Serial No. 76,812

Claims priority, application Great Britain
May 10, 1948

3 Claims. (Cl. 102—7)

1

This invention concerns fins for projectiles, more particularly for use with sea mines launched from aeroplanes.

An object of this invention is to provide an improved construction of stabilising fin which is capable of being folded against the projectile so that the room taken up in stowing the projectile is substantially reduced.

Another object is to provide for automatic unfolding of the fins when the projectile is launched.

Yet a further object of the present invention is to provide a construction of fin which may be readily folded and which, when unfolded, is simply and effectively supported against deflection by the aerodynamic forces acting on it.

According to the present invention the fins of a projectile are carried by a frame, adjustably attached to the projectile, for pivotal movement and are urged from a folded position against the projectile to a position radially of the projectile and the fins are adapted initially to be held, each independently, in folded position to the frame by a catch, all said catches being simultaneously unfastened from the frame and connected with a common release gear by adjustment of the frame on the projectile.

With this arrangement each fin may be folded and held in position by its catch and this operation may be done by one person. When all the catches are engaged the release gear may be connected to them and the catches then released in a simple manner without great effort. It will be seen, therefore, that the operation of folding the fins, and connecting them to the release gear, does not call for several persons acting on the fins at the same time.

According to another feature of this invention each fin is spring-urged to its unfolded position the spring acting on the fin through a link, one member of which is carried around with the fin when the latter is unfolded so that one of its ends enters, and is held in, a slot of the frame in such a position that aerodynamic forces on the fin are applied by said member to the sides of the slot and are not transmitted to the spring.

Each fin-holding catch preferably comprises a pin having a pair of spaced heads, the shank of the pin being adapted to enter an open-ended slot in the frame and fin so that the spring pull on the fin is taken by the heads. The release gear preferably comprises, for each catch, a rod secured to that head of the pin which engages the frame and a common anchorage for all said rods the arrangement being that when the frame

2

is axially adjusted, as indicated, the pin disengages the frame.

A practical application of the present invention will now be described by way of example only, with reference to the accompanying drawings whereof:

Figure 1 is a side elevation of a sea mine in accordance with the present invention,

Figure 2 is a view in the direction of the arrow 10 of Figure 1 and to an enlarged scale,

Figure 3 is a view in the direction of the arrow 3 of Figure 2 showing the fins and fin-attachment means of the sea mine in Figure 1 to an enlarged scale and partly in section.

Figure 4 is a similar view to Figure 2 and showing certain parts of the fins and attachment means in section, and

Figure 5 is a scrap view showing a detail of construction of the attachment means.

Referring to Figures 1 and 2 of the accompanying drawings: the sea mine is generally indicated by the reference numeral 10 and comprises a mine 11 and a fin system 12 and attachment means therefor. The fin system is removably attached to the mine 11 and comprises four fins 13 which are hinged at 14 (Figure 2) to a frame 15, the fins being capable of being folded against the frame or of being swung outwardly so as to lie radially of the mine. The frame 15 is attached to the mine 11 by a device which permits the fin system to be automatically thrown off on impact of the mine with the sea.

Referring now to Figures 2, 3 and 4: it will be observed that the frame 15 comprises a cylindrical member 16 having a pair of axially spaced flanges 17 of square outline (Figure 2). A fin 13 is pivoted at each corner of the flanges 17, the fins being preferably mounted on tubes 18 (Figure 3) which extend from one flange to the other. The frame 15 is placed over one end of the mine 11 which enters the cylindrical part 16 of the frame.

Each fin 13 normally lies along one edge of the square frame 17 as is clear from Figures 2 and 4. The mine is stowed in the aircraft with the fins folded so that the amount of room taken up is as small as possible. When the mine is launched the fins are automatically unfolded and assume their radial position—see the 50 chain dotted position of the fin 13 in Figure 4.

To hold the fins in the folded position there is provided for each fin a catch comprising a pin 19 having spaced heads 20, 21 (Figure 5). Each fin is formed with an upstanding flange 22 and 55 there is formed in the flange an open-ended slot

23. The upper end of the cylindrical part 16 of the frame 15, at a point opposite the slot 23, is also formed with an open-ended slot 24. It is arranged that when a fin is folded against the frame 15 the open-ended slots 23, 24 are brought opposite each other and the shank of the pins 19 enters the slots so that the heads 20, 21 of the pin engage the cylindrical part 16 and the flange 22 respectively. Each fin 13 is spring urged to assume its unfolded position and the pin 19 applies the pull of the spring to the cylindrical part 16 and the fin is therefore held folded.

Each pin 19 is connected by a rod 25 to a common anchorage 26 disposed towards the centre of the frame 15. The anchorage comprises a bracket 27 through which there passes a hook 28. The shank of the hook is threaded through an opening in each of the rods 25. The hook 28 is connected by a cable to the aircraft when the mine is stowed.

The bracket 27 projects to within the cylindrical part 16 of the frame 15 as shown in Figure 3 and it is arranged that when the frame is placed in position on the mine 11 the end of the mine engages the bracket 27 and displaces it axially by an amount such that the heads 20 of the pins 19 are raised clear of the part 16 i. e. the pins 19 are moved out of the slots 24. The spring pull on each fin will then be transmitted through the pin 19 and the rod 25 to the common anchorage 26. In this way after the frame 15 has been applied to the mine 11 the fins 13 are held in their folded position by the rods 25 and anchorage 26.

With the arrangement described, each fin 13 may be individually moved to its folded position and is associated catch pin 19 placed in position so that the fin is held to the frame 15. When the four fins are thus held in their folded position each catch is connected by the rod 25 to the common anchorage 26. The frame is then slid over one end of the mine 11 and in so doing the bracket 27 is axially displaced simultaneously to release the four catch pins from the part 16 of frame 15. The tendency of the fins to unfold is then resisted by the rods 25 and anchorage 26 which constitute with the pins 19 a release gear for the fins.

When the mine is launched the cable removes hook 28 and thus releases the rods 25 and the fins 13 fly outwardly, the rods 25 and pins 19 being thrown clear by this action. The pins 19 will readily disengage the fins 13 since they are only held in the open ended slots 23. The fins 13 will be pulled outwardly to their radial position by the spring means referred to above.

Each fin 13 carries an arm 29 (Figure 4) which is pivotally connected to a link 30 at 31. The free end 39 of the link 30 engages the surface 32 of a slide 33 which is secured to the part 16 of frame 15. The free end 39 of the link 30 is adapted to slide along the surface 32 and into slot 34 between the slide 33 and a finger 35. A spring 36 is anchored at 37 to the link 30 and at 38 to a bracket carried by the part 16. The spring 36 is the spring referred to above which is provided to move the fin 13 from the folded to the unfolded position.

When the fin 13 is in its folded position the arm 29 and link 30 are in line and lie generally along one side of the edge of the flange 17 (see the full line position—Figure 4). When the fin is released in the manner described above the spring 36 rotates the fin 13 and the arm 29 and link 30 are carried around with the fin. The arrangement is that as the fin swings outwardly the free

end of the link 30 is drawn along the surface 32 to within the slot 34. When in the unfolded position (shown in chain dotted lines in Figure 4) the arm 29 and link are nearly at right angles and the free end of the link 30 is held within the slot 34 by the spring 36. Aerodynamic forces acting on the fin 13 are transmitted by the arm 29 to the link 30 and thence to the sides of the slot 34. The line of action of the forces on the link 30 will be against the sides of the slot 34 and will therefore not be applied to the spring 36. The tension in the spring is only applied to maintain the free end of the link 30 within the slot 34.

With the arrangement described the strength of the spring 36, since it does not require to support the fin against the aerodynamic forces acting on it, may be relatively light and this, taken in conjunction with the catch pins 19 enables one person to turn each fin in succession to its folded position.

Reference has been made above to the provision of a device for disengaging the frame 15 from the mine 11 when the latter strikes the surface of the water. The purpose of this is to enable the mine to sink without the fin system as it is considered undesirable that the fins should control the passage of the mine through the water.

The device referred to is generally indicated by the reference numeral 50 in Figures 2, 3 and 4 and will now be described with reference to these figures. The part 16 of the frame 15 carries a bracket 40 which is spaced from the right-hand flange 17 of Figure 3 and which is connected to it by a rod 41. The bracket 40 also carries a lever 42 which is pivoted at 43. One arm of the lever 42 is constituted as a finger 43 which passes through an opening 44 in the part 16 to engage the cylindrical surface of the mine 11. A spring 45 presses the finger 43 inwardly to engage the mine. The other arm 46 of the lever 42 lies beneath a weight 47 which is adapted to slide along the rod 41. The weight 47 is normally held clear of the arm 46 by a locking wire 48 which passes through a hole in the rod 41. Prior to the frame being attached to the mine 11 the weights 47 are raised and the locking wires 48 secured in position so that the weight is held clear of the frame 46. When the frame 15 is placed on the mine 11 the finger 43 will engage the cylindrical wall and being pressed against it will hold the frame 15 in position.

It will be noted that the finger 43 does not prevent the frame 15 from being slid axially to displace the anchorage 26 for the purpose of withdrawing the pins 19 from the slots 24 as described above.

When the mine strikes the water the impact urges the weight 47 to the bottom of the rod 41. The strength of the wire 48 is selected so that it is sheared through under these conditions and the weight 47 will descend to strike the arm 46 and withdraw the finger 43 from the mine 11. The mine will therefore be free to slide out of the part 16 of the frame 15. Two such devices 50 are provided at diagonally opposite corners of the frame 15 as shown in Figure 2.

It will be understood that the present invention is not limited in its application to sea mines. The collapsible fin arrangement described finds application to bombs and torpedoes of large size where the fins unless collapsed would take up an excessive amount of storage room.

I claim:

1. For a projectile, a fin assembly comprising a frame having an open ended slot therein, a plu-

rality of fins having open ended slots pivotally mounted on the frame, means urging each fin from a folded position against the frame to an extended position projecting from the frame, separate catch pins having a pair of axially spaced heads, the shank of the pin being adapted to enter the open ended slots in said frame and fin so that the force urging the fin to its extended position is taken by the heads of the pin, a plurality of separately folded radiating arms, an anchorage centrally of the arms, means releasably connecting the separately folded arms to said anchorage, means connecting each arm to one of the separate catch pins, and means for simultaneously releasing the separate catch pins from all the fins and for simultaneously connecting the fins to the central anchorage by said radiating arms.

2. A fin assembly as claimed in claim 1 wherein the central anchorage of the radiating arms is 20 adapted to be engaged by the projectile and is so arranged that when the assembly is fitted into its final position on the projectile the anchorage is moved to withdraw the pin from the open ended slot in the frame.

3. A fin assembly as claimed in claim 2 wherein there is provided for each fin a plate having an open-ended slot which extends substantially normal to the fin when the latter is in the fully

extended position, a spring urging each fin to its fully extended position, the force of the spring being applied to the fin through a linkage comprising a pair of pivotally connected members of 5 which one is substantially normal to the fin and the free end of the second is strained by said spring to travel along one side of, and enter, said slot that limits the extent of movement of the second member so that when the fin is fully 10 extended the pair of pivotally connected members are at substantially right angles to one another and the second member is substantially normal to the length of the slot whereby the aerodynamic forces on the fin are applied through said members to the sides of the slot.

EVELYN CECIL MUSCHAMP D'ASSIS
FONSECA.
